UNITED STATES PATENT OFFICE.

NOAH L. COCHEU, OF BROOKLYN, N. Y., ASSIGNOR TO HIMSELF, TIMOTHY YOULE BROWN, OF NEW YORK, AND GEORGE BROWN WALTON, OF BROOKLYN, N. Y., TRUSTEES.

PROCESS OF MANUFACTURING ELECTROTYPE-ROLLERS FOR IMITATING LEATHER AND OTHER MATERIALS.

SPECIFICATION forming part of Letters Patent No. 276,777, dated May 1, 1883.

Application filed July 6, 1882. (No model.)

To all whom it may concern:

Be it known that I, NOAH L. COCHEU, a citizen of the United States, residing at Brooklyn, in the county of Kings and State of New York, have invented certain new and useful Improvements in Process of Manufacturing Electrotyped Rollers for Imitating Leather and Other Materials; and I do hereby declare the following to be a full, clear, and exact description of the invention, reference being had to the accompanying drawings, which form part of this specification, in which—

Figure 1 is a side elevation of a forming-roll. Fig. 2 is a longitudinal section of leather tube, with backing or stiffening. Fig. 3 is a side elevation of spiral electrode. Fig. 4 is a view showing transverse section of leather tube with backing and end of spiral electrode. Fig. 5 is a longitudinal section of completed tubular electrotyped roller.

Efforts have been made heretofore to produce, by means of the deposition of copper upon molds of wax and other substances electrotypes of cylindrical form, the outer surfaces of which should be unbroken and seamless and contain an exact copy or design of the material or mold on which the deposit was made; but none prior to my invention have proved satisfactory. Flat electrotype-plates have been made by deposition upon leather and bent around a shaft or bar of metal, the joint being soldered and the whole soldered or cemented to said shaft or bar. Such method is objectionable for these reasons: first, that it is found impossible to make an accurate joint and one that will stand the pressure necessary for embossing purposes; second, it has been found difficult, if not impossible, by such method to obtain a roller perfectly cylindrical in form. Again, attempts have been made to accomplish the object sought by using a mold of iron or other substance, the inner surface of which is circular in form and perfectly smooth, and which is made in two parts, the joints being at each side and running from one end to the other of said mold; the two parts of the mold being separated, each was lined with leather, (when the object to be imitated was leather,) and the leather cut along

the edge of the mold, so as to fit and completely cover the interior of said mold when its two parts were joined, the grained surface of the leather being exposed to galvanic action in an electrolyte composed of a solution of sulphate of copper, acid, and water. This method is also objectionable for these reasons: first, because no skin of leather is of uniform thickness, and if a cylindrical mold such as described be lined with it the deposit will take the form of the cavity formed by the leather, and not of the cylindrical mold, and will present an uneven surface, corresponding to the variations in the thickness of the leather in its different parts; second, in lining such cylindrical mold it is necessary to cause the back or ungrained part of the leather to adhere to said mold by means of heated wax, pitch, cement, or similar substance, and it is impossible to obtain a perfectly-even coating of the interior of the mold of sufficient thickness to secure the adhesion of the leather, so that the unevenness of such adhesive coating is reproduced on the surface of the deposited roller when completed; third, should the said adhesive substance fail to secure the leather to all parts of the interior of the mold such portions as are not fastened will swell and warp in the solution and the effects be reproduced in the deposits, the roller will not be truly round, and by reason of the unevenness of its surface a perfect impression of what was intended to be reproduced cannot be obtained, the face of the material will show in some parts a bold and vigorous impression, while in other parts a slight impression or none whatever will be seen.

The object of my invention is to produce a tubular electrotyped roller for the purpose specified, which shall be of copper or other metal the salts of which may be decomposed by galvanic action, which shall be solid in all its parts, perfectly round, and possessing none of the imperfections noted above. In order to produce such a roller, I prepare the surface of the leather or other material upon which I desire to make the deposit so that it will resist the action of the acid in the solution. For this purpose the leather may be coated, or, if neces-

sary, saturated with a mixture of wax and turpentine; but any other suitable materials may be employed. I metallize the surface as in ordinary electrotyping, so that it may more quickly receive the deposit. I then cut the leather to the proper size and shape and wind it spirally around a roller of iron or other substance of the desired size, which has been turned in a lathe to perfect accuracy; and the surface of which is perfectly smooth, the grained surface of the leather or other material being in contact with the surface of said roller.

In the drawings, A represents the roller, and B the strip of leather or other material to be copied, wound spirally around the same. I next bind the leather in place by means of a strip of coarse netting or other material having open meshes, such binding strip being shown at C. I then apply a stiffening substance of paraffine, gutta-percha, or other equivalent material to the outside of the leather or other material by means of a brush, or by causing it to revolve in a trough containing the stiffening substance in solution or in a melted state until a coating is obtained of sufficient thickness to prevent alteration of its form or shape. After such coating is thoroughly dried or cooled I withdraw the metal or internal roller, leaving the leather or other material so inserted in one piece without joints, the interior of which corresponds accurately in size and form to the surface of the roller upon which it was formed. The tube thus formed is shown in Fig. 2, the letter D indicating the coating, C the netting, and B the leather or other material upon which the deposit is to be made. I next suspend in the tube so formed a metallic electrode of spiral or corrugated form for the purpose of securing greater surface for the action of the electrolyte. My reasons for using an electrode of the form suggested are as follows: First, the surface of a positive electrode should be not less than that of the material receiving the deposit, otherwise the deposit is not likely to be good, more care is required, and the electrolyte becomes weaker; second, by the use of an electrode such as described the surface thereof may be made to correspond as nearly as possible in area to the surface of the material receiving the deposit, while occupying a comparatively small space and subject to the action of the electrolyte on all its parts.

E in the drawings represents a spiral electrode, for which one of corrugated form may be substituted as an equivalent.

While I prefer the above described form of electrode, still I do not claim it as a necessary part of my invention.

Having inserted the electrode in the tube, I place the whole in a decomposition-tank containing the electrolyte, make the proper connections with a galvanic battery or dynamo-electric machine, by the action of which the metal in solution is deposited upon the leather or other material to any required thickness, after which the whole is removed from the solution, the leather or other material detached, and the newly-formed electrotyped roller F, the outer surface of which is perfectly round, is placed in a lathe, the inside bored out smooth, and the tube made of an even or uniform thickness is then driven on a metallic shaft, F', which is turned to fit tightly. The tubular roller may be keyed on said shaft, if desired or necessary.

By the method above described as my invention electrotyped tubular rollers may be made of many sizes and designs, and used in an ordinary embossing-press.

I do not herein claim the product which results from the new process herein described and claimed, as I intend making said product the subject of another application for Letters Patent.

What I claim as my invention is as follows:

The method herein described of forming electrotyped tubular rollers, consisting in the following steps: first, applying a protective coating to and winding a strip of leather or other material to be imitated on a roller or cylinder; second, applying a backing of stiffening substance to the outer or exposed surface of the leather or other material; third, withdrawing the forming roller or cylinder after the stiffening has dried or cooled; fourth, inserting a positive electrode in the formed tube of leather or other material and producing by galvanic action a metallic deposit on the inside of the latter; fifth, taking off the leather or other material exterior to the deposited metal; and, sixth, fitting the tube on a shaft, substantially as set forth.

In testimony that I claim the foregoing I have hereunto set my hand this 5th day of July, 1882.

NOAH L. COCHEU.
